Atty.

UNITED STATES PATENT OFFICE.

CORNELIUS BRITIFFEE TULLY, OF WESTMINSTER, ENGLAND.

GAS WASHING AND CONTROLLING APPARATUS.

Application filed January 24, 1920. Serial No. 353,909.

To all whom it may concern:

Be it known that I, CORNELIUS BRITIFFEE TULLY, a subject of the King of Great Britain and Ireland, residing at Westminster, England, have invented Improvements in Gas Washing and Controlling Apparatus (for which I have filed application in England No. 6,876 of May 14, 1917, Patent No. 112,091), of which the following is

10 a specification.

This invention has reference to gas washing and controlling apparatus suitable for use with a gas producer and it has for its object to provide apparatus adapted to control the exit of hot gas from a gas producer, to wash and cool the gas during its passage through the apparatus and at the same time, to maintain the apparatus in a cool condition.

20 For this purpose gas washing and controlling apparatus according to the invention comprises a closed box or casing provided with a vertical gas inlet pipe or branch the upper end of which is adapted to be connected by a pipe to the gas outlet of the gas producer and the lower end of which extends into the box and is controlled by a valve carried by valve operating means capable of being actuated from the exterior 25 of the valve box for the purpose of opening and closing the valve, the box being also provided with liquid inlet and outlet branches and internally with an upwardly extending partition adapted to maintain 30 liquid, for example water, which by means of the said inlet and outlet is caused to flow continuously therethrough, at a suitable height above the bottom of the inlet pipe or branch so that such liquid during its passage through the box, will wash and cool the gas passing through the gas inlet branch and also cool the valve and keep it clean, the washed gas then flowing to an outlet, over the said partition.

40 The apparatus is distinguished from a seal box provided with valved gas inlet and outlet pipes as heretofore proposed since in such case no provision exists for washing the gas by a continuous flow of liquid 45 besides which by the present invention liability of the seal becoming ineffective through loss of the sealing liquid is wholly obviated.

Gas washing and controlling apparatus, 50 such as described may advantageously be used in connection with a gas producer hav-

ing upper and lower gas exit branches through which water gas, methane hydrogen or other gas produced in the generator is caused to flow alternately in a manner well understood. In this case the valve box is provided with two inlet pipes or branches each provided with a controlling valve and independent means for opening and closing it at will.

55 In the accompanying illustrative drawings, Figs. 1 and 2 show respectively in longitudinal section and transverse section and Fig. 3 in sectional plan, gas washing and controlling apparatus according to the invention provided with two gas inlet valves. Fig. 4 shows in side elevation how the apparatus can be used in connection with a gas producer.

60 In this example shown, *a* is a box provided with a cover *b* through which extend two vertical gas inlet pipes or branches *c* and *d* provided with flanges *c*¹ and *d*¹ for making gas tight connections with the cover of the box and with flanges *c*² and *d*² 65 for making similar connections, as shown in Fig. 4, to pipes *e* and *f* extending from gas exit branches *g* and *h* at the bottom and top respectively of a gas generator *i*, *t* is the inlet branch for water which passes 70 through the box and finds its outlet as hereinafter more fully set forth. The lower end of each gas inlet pipe *c* and *d* is controlled by a disc valve *j* jointed to a lever arm *k*, one end of which is pivoted to the lower 75 end of a supporting rod *m* fixed to the cover *b* of the box. The other end of the lever arm *k* is suitably jointed to the lower end of an operating rod *n* that extends in a gas tight manner through a gland *o*, carried by 80 the cover *b* to the exterior of the box *a* where it can be operated by hand in any convenient manner, either directly or through intermediate mechanism, as lever mechanism, for raising or lowering the lever arm *k* and closing or opening the corresponding valve *j*, means not shown, being provided for holding the operating rod *n* and attached parts in the valve closing or 85 opening position at will. *p* is a vertical partition the upper end of which terminates some distance above the lower ends of the pipes *c* and *d* and valves *j*, to form with the sides and bottom of the box *a*, a receptacle 90 through which water can be caused to continually flow, the level of which will be above the lower ends of the pipes so that

100

105

110

hot gas escaping therethrough will be cooled and partly washed by the current of water which will also cool the valves and keep them free from dust or other solid matter. *r* is a lateral outlet branch through which the cooled and washed gas, after flowing over the top of the partition *p*, can flow to a pipe *s* (Fig. 4) and can be led where required. An outlet branch is provided through which water entering by the inlet *t* can, after flowing over the top of the partition *p*, escape. The water outlet may, as shown, be constituted by the gas outlet branch *r*. In this case the gas and water flow off together through the outlet branch *r* and are afterwards separated from each other in any known or suitable way.

The box *a* may be provided with one or more laterally arranged clearing or inspection holes *u* normally closed, or each closed, by a cover or door *v* held in place by a screw *w* working through a removable cross bar *x*. This bar in the example, normally rests on a pair of laterally extending supporting bars *y* carried by the box *a* and which also serves to support lugs *v*¹ on the door *v* and are provided at their outer ends with upwardly bent ends *y*¹ to serve as abutments for the cross bar *x* when tightening up the screw *w*.

As will be seen the gas inlet pipes *c* and *d* with valves and valve operating mechanism are all carried by the removable cover *b* of the box *a* so that free access can be gained to the interior of the box for cleaning or other purpose upon removal of the said cover.

Having now particularly described and ascertained the nature of my said invention and in what manner the same is to be performed, I declare that what I claim is:—

1. Gas washing and controlling apparatus, suitable for use with a gas producer, comprising a covered box having an inlet for washing and cooling liquid and outlet means for liquid and gas, a gas inlet pipe extending into said box, a valve adapted to open and close the lower open end of gas inlet pipe, valve opening and closing

means located within said box, means extending from the interior to the exterior 50 of the box whereby the valve opening and closing means can be operated from the exterior of the box and means located within the box for maintaining the surface of the liquid, during its passage through the 55 box, at a height some distance above the lower end of the gas inlet pipe and its controlling valve.

2. Gas washing and controlling apparatus, suitable for use with a gas producer, 60 comprising a box having a removable cover, an inlet for washing and cooling liquid, outlet means for washed and cooled gas and for liquid, and a partition for maintaining a constant depth of liquid in said box, a gas inlet pipe carried by and extending through said removable cover and terminating below the top of said partition, a valve for opening and closing the lower end of said pipe, a lever for carrying and operating said valve, means carried by the said removable cover to which one end of the lever is pivoted and operating means connected to the opposite end of the lever and extending in a gas tight manner through said 75 removable cover.

3. Gas washing and controlling apparatus, comprising a box having a removable cover, an inlet for washing and cooling liquid, at one end an outlet branch for liquid and gas, and a transverse vertical partition between said liquid inlet and said outlet branch, a gas inlet pipe carried by and extending through the cover of the box to a level below the top of said partition, a disc valve arranged below and controlling the lower end of said gas inlet pipe, a lever carrying said valve, a supporting rod carried by said cover and to which one end of said lever is jointed and an operating rod connected to the opposite end of said lever and extending in a gas tight manner through the said removable cover.

Signed at London, England, this 5th day of January 1920.

CORNELIUS BRITIFFEE TULLY.
